CAN OPENER

Tadeusz Zaremba, Warsaw, Poland

Application January 29, 1935, Serial No. 3,957
In Poland February 1, 1934

7 Claims. (Cl. 30—15)

I have filed an application in Poland on the 1st February, 1934.

The present invention relates to an improved can opener. The main object of the invention is 5 to provide a can opener in which the traction wheel performs in addition to the known rotary movement which propels the opener along the rim of the can, a further movement relatively to the cutter, which is directed towards the cutter, which is directed towards the cutter, 10 in such manner that upon the traction wheel coming into contact with the bead of the can, the cutter is drawn towards and into the wall of the can, whereby the wall of the can is cut through and the cutter is pressed into the wall. During 15 the further rotation of the traction wheel, the wall of the can is then cut by the cutter in the usual manner.

The improved can opener according to the invention can be supplied separate from the can 20 and used many times in connection with various cans, or it can be supplied with a particular can in which case it is placed by the manufacturer at once in the correct position upon the can. The can opener can be used either for cutting the 25 peripheral wall of the can or the cover, the cut being in either case in the vicinity of the rim or bead. It can be used in connection with cans having beads of various vertical dimensions, inasmuch as the traction wheel automatically 30 adjusts itself during the cutting operation for the required size of bead.

An important feature of the improved can opener is a guide slot which produces a required relative movement between the traction wheel 35 and the cutter blade or vice versa, and determines the direction of this movement, as well as other means which convert the turning movement imparted to the traction wheel into the required relative movement between the wheel and the 40 cutter blade. As the improved can opener is provided with means for varying the distance between the cutter blade and the traction wheel, it can be very easily placed upon a can or tin and be removed therefrom.

45 Several constructional forms of the improved opener are shown in the accompanying drawing, in which:

Fig. 1 is an elevation of the opener seen from the interior, that is, from the side of the cutter blade,

Fig. 2 is an end view,

Fig. 3 is an elevation of the opener seen from the exterior, that is from the side of the handle,

Fig. 4 is a plan corresponding to Fig. 1,

Fig. 5 is an end view showing the can opener

applied to a tin, the parts being shown in the cutting position of the opener.

Figs. 6, 6a, 6b and 7 show a modified construction, Fig. 6 being an elevation of the shield, Figs. 6a and 6b showing details, and Fig. 7 being a sectional elevation.

Figs. 8, 8a and 8b show a further modification, Fig. 8 being an elevation of the shield seen from the side of the cutter blade, and Figs. 8a and 8b showing details.

Fig. 9 shows a further modification of the shield in elevation seen from the side of the cutter blade.

Figs. 9a and 9b illustrate details appertaining to the construction shown in Fig. 9.

Figs. 10, 10a and 10b show a further modification, Fig. 10 being an external view of the shield, and Figs. 10a and 10b showing details.

Fig. 11 shows the construction according to Figs. 1 to 5 with an additional device for securing the whole can opener to a can in the required initial position.

Referring first to Figs. 1 to 5, the can opener comprises a shield 1 provided with a guide slot 2 and a handle 3 which latter forms a unit with a traction wheel 4 a guide wheel 5 and a collar 15. The shield 1 has at its lower end a lug 7 which forms an abutment bearing against a portion of the tin. The middle or central portion of the lug 7 has a straight edge exactly parallel to the surface of the shield so that the can opener on being placed upon a can will always be located at the same angle no matter whether the side of the can is cylindrical or plane. The upper edge of the shield is in its middle portion bent to form a cutter blade 8 having an inclined cutting edge as shown. The slot 2 serves for guiding the handle 3 and the parts connected with the handle, namely the traction wheel 4, the guide wheel 5 and the collar 15. The upper portion 9 of the guide slot 2 is arranged at an angle relatively to the main portion of the slot 2 either in the one or in the other direction and serves as a bearing or support for the guide wheel 5 during the cutting operation. As will be seen from the drawing, the traction wheel 4 and the collar 15 are located on opposite sides of the shield 1 whilst the guide wheel 5 is located in the guide slot 2, and consequently the handle 3 can be not only turned, but also displaced bodily in the slot.

The relative movement of the traction wheel towards and away from the cutter blade is in this construction produced by projections 6 and 6' formed upon the handle 3 by suitably cutting and bending portions thereof, these projections being adapted to cooperate with a pin 10 carried

by the shield. On rotating the handle 3 in the direction of the arrows shown in Fig. 3, projection 6 strikes the pin 10, and as the guide wheel 5 is guided in the slot 2, the whole handle with 5 the parts attached thereto is moved upwards, the cutter blade 8 being simultaneously moved downwards towards the cover of the tin. Assuming that the device has been placed upon a tin 10 with a view to cutting the cover along the inner side of the rim, the cutter blade penetrates gradually into the cover and pierces the cover as shown in Fig. 5, the toothed traction wheel 4 simultaneously coming into contact with the lower edge of the bead. At the same time, the guide 15 wheel 5 is moved towards the inclined extension 9 of the guide slot. As the cutter blade rests during the commencement of this operation upon a still solid portion of the cover, the traction wheel 4 will be firmly pressed into the bead of 20 the tin.

The extended slot portion 9 serves also as a means for moving during the upward movement of the handle the engaged members away from each other so as to permit of a further rotation 25 of the handle. This further rotation of the handle then causes the opener to move along, the cover of the tin being during this movement completely cut by the cutter blade 8. It is not essential that the projections 6 and 6' be bent 30 away laterally from the handle 3, this construction being shown only as a convenient one from the manufacturer's point of view. If preferred, the projections 6 and 6' might be arranged in the line of the handle.

35 By suitably applying the device to the cover of the tin, the peripheral side of the tin can be cut through.

The modification shown in Figs. 6, 6a, 6b and 7 differs from the construction just described only 40 in that the collar 15 of the first construction is replaced by a lifting wheel 12 formed with two recesses 11 arranged diametrically opposite each other. The projections 6 and 6' are omitted. Otherwise the construction is the same as shown 45 in Figs. 1 to 5. On turning the handle 3' a flank of a recess 11 encounters the pin 10 of the shield and the whole handle together with the wheels 4, 5, and 12 is moved upwardly, that is, towards the cutter blade, this movement causing again 50 the cutter blade to pierce the can as previously described.

The modification shown in Figs. 8 to 10b refers 55 to the shape of the guide slot 2 in the shields 1', 1'', 1''' and to the construction of the guide wheel and the lifting wheel. In the modification according to Figs. 8, 8a and 8b the wall bounding the slot 2 is provided with a projection 60 or tooth 13 and the guide wheel 14 serves both for guiding and for lifting the handle, the 60 collar 15 is, in this case circular and serves, as in the construction shown in Figs. 1 to 5, merely for holding the handle in the slot 2. The guide wheel 14 is provided with a recess 13' which, during the turning of the handle, encounters the 65 tooth 13 and moves the traction wheel relatively to the cutter blade in the manner previously described. In this construction the guide slot has not the extended portion 9.

The construction shown in Figs. 9, 9a and 9b 70 differs from the construction according to Figs. 8, 8a and 8b only in that the guide and lifting wheel 16 is in the form of a toothed wheel, the guide slot 2 of the shield 1'' being provided with corresponding teeth 17. Upon rotation of the 75 handle the toothed wheel 16 engages the teeth

of the slot and the same action, namely, relative movement between the traction wheel and the cutter blade is produced.

In the construction according to Figs. 10, 10a and 10b, the guide wheel 5 is constructed as in Figs. 1 to 7. The lifting wheel, however, has the form of a toothed wheel 18. This toothed wheel is adapted to engage between pins 10 provided upon shield 1''. By this engagement, the handle 5 is moved upwardly and the cutter blade is again 10 caused to enter and pierce the can.

In place of the lifting wheel, the traction wheel 4 may be used which, in this case, may mesh with a short toothed rack fixed upon the shield upon the inner side, that is, upon the side corresponding to the cutter blade 8. The guide slots 2, or 9, may be arranged at any desired angles relatively to the cutting edge of the plate 8; they may consist of a continuous guide slot of arcuate shape, or of any suitable curved shape.

The relative movement of the traction wheel 4 and the cutter blade 8 may also be obtained by an arrangement in which a traction 4 rotatably mounted in the shield of the opener imparts to the cutter blade 8 the required relative movement, said cutter blade being for this purpose mounted upon a toothed rack slidable relatively to the shield and engaged by the traction wheel.

In some cases manufacturers supply a can 30 opener with each tin and place the opener in the required position upon the tin in order to save customers the trouble of applying the opener to the tin. In order to prevent the tin opener from being accidentally operated in such cases 35 before it is intended to open the tin, the shield 1 is, as shown in Fig. 11, provided with a retaining plate or member 19, the ends of which are bent to engage on the one hand the tin 40 opener and on the other hand the rim of the tin, as shown in Fig. 11. This retaining member prevents accidental depression of the cutter blade 8 and consequently piercing of the tin. On actuating the tin opener, the retaining member is automatically put out of action owing to the 45 fact that the bent portions 20 are straightened by the force used in turning the handle 3, 3', whereupon the opener will be actuated in the manner previously described.

It will be understood that various modifications are possible within the scope of the invention, which generally comprises any construction in which means are provided for obtaining a relative movement between the traction wheel and the cutting blade by the operation of the handle 55 or traction wheel.

I claim:

1. A can opener, comprising in combination: 60 a shield; a fixed wedge-shaped cutter blade on said shield; a traction wheel provided with a handle for rotating same; and means for relatively moving said cutter blade and said traction wheel towards and away from each other operable by rotation of said handle, said means comprising: a guide slot in which the traction wheel with the handle is slidably mounted, said guide slot being placed in such a manner relatively to the rear edge of the knife, that it is always in front of said edge, considered in the direction of the movement of the can opener during cutting.

2. A can opener, comprising in combination: 65 a shield; a fixed wedge-shaped cutter blade on said shield; a traction wheel provided with a handle for rotating same; and means for rela- 70

- 5 tively moving said cutter blade and said traction wheel towards and away from each other operable by rotation of said handle, said means comprising: a guide slot in which the traction wheel with the handle is slidably mounted, said guide slot being placed in such a manner relatively to the rear edge of the knife, that it is always in front of said edge, considered in the direction of the movement of the can opener during cutting, and said guide slot consisting of two arms, one of which is located below the knife, whilst the other is arranged at an angle to the first arm for the reception and guiding of the traction wheel during the actual cutting operation.
- 10 5 15 10 15 20 25 30 35 40 45 50
- 15 3. A can opener, comprising in combination: a shield; a fixed wedge-shaped cutter blade on said shield; a traction wheel provided with a handle for rotating same; and means for relatively moving said cutter blade and said traction wheel towards and away from each other operable by rotation of said handle, said means comprising: a guide slot in which the traction wheel with the handle is slidably mounted, said guide slot being placed in such a manner relatively to the rear edge of the knife, that it is always in front of said edge, considered in the direction of the movement of the can opener during cutting, and a projection upon said shield and a member associated with said traction wheel and adapted upon striking said projection to move said traction wheel towards said cutter blade.
- 20 25 30 35 40 45 50
- 25 4. A can opener comprising in combination: a shield; a fixed wedge-shaped cutter blade on said shield; a traction wheel provided with a handle for rotating same; and means for relatively moving said cutter blade and said traction wheel towards and away from each other operable by rotation of said handle, said means comprising: a guide slot in which the said traction wheel with the handle is slidably mounted, said guide slot being placed in such a manner relatively to the rear edge of the knife, that it is always in front of this edge, considered in the direction of the movement of the can opener during cutting, and projections upon said shield and a member associated with said traction wheel and adapted to co-operate with said projections upon the shield.
- 30 35 40 45 50
- 30 5. A can opener comprising in combination: a shield; a fixed wedge-shaped cutter blade on
- 5 10 15 20 25 30 35 40 45 50
- 5 said shield; a traction wheel provided with a handle for rotating same; and means for relatively moving said cutter blade and said traction wheel towards and away from each other operable by rotation of said handle, said means comprising: a guide slot in which the traction wheel with the handle is slidably mounted, said guide slot being placed in such a manner relatively to the rear edge of the knife, that it is always in front of this edge, considered in the direction of the movement of the can opener during cutting, and a tooth in the guide slot in said shield, and a member associated with said traction wheel and adapted to co-operate with said tooth of the slot.
- 10 15 20 25 30 35 40 45 50
- 15 6. A can opener comprising in combination: a shield; a fixed wedge-shaped cutter blade on said shield; a traction wheel provided with a handle for rotating same; and means for relatively moving said cutter blade and said traction wheel towards and away from each other operable by rotation of said handle, said means comprising: a guide slot in which the traction wheel with the handle is slidably mounted, said guide slot being placed in such a manner relatively to the rear edge of the knife, that it is always in front of this edge, considered in the direction of the movement of the can opener during cutting and a cam slot having a toothed portion, and a member associated with said traction wheel and adapted to co-operate with said toothed portion.
- 20 25 30 35 40 45 50
- 25 7. A can opener comprising in combination: a shield; a fixed wedge-shaped cutter blade on said shield; a traction wheel provided with a handle for rotating same; and means for relatively moving said cutter blade and said traction wheel towards and away from each other operable by rotation of said handle, said means comprising: a guide slot in which the traction wheel with the handle is slidably mounted, said guide slot being placed in such a manner relatively to the rear edge of the knife, that it is always in front of this edge, considered in the direction of the movement of the can opener during cutting and means for holding said cutter blade in an inoperative position on application of a can opener to a can, said means consisting of a retaining plate or member engaging the lower edge of said shield and the rim of a can.
